UNITED STATES PATENT OFFICE

HERBERT P. RENWICK, OF CHICAGO, ILLINOIS, ASSIGNOR TO STAR SPECIALTY MFG. COMPANY, OF CHICAGO, ILLINOIS, A CORPORATION OF ILLINOIS

EXHAUST HEATER

Application filed January 6, 1928. Serial No. 244,822.

The invention relates generally to exhaust heaters for automotive vehicles of the type wherein air is conducted through a casing which surrounds a portion of the exhaust pipe of the engine and is passed on into the body of the vehicle.

It is the primary object of the present invention to provide a novel exhaust heater of this type which may be easily installed by relatively unskilled persons and which is of such a universal character as to be adaptable for installation on exhaust pipes of different diameters.

In attaining this object I provide a heater casing of one standard size which will provide sufficient heating space when used with any of the sizes of exhaust pipes which are encountered in ordinary cars and embodying adjustable means adapted to fit the casing about any exhaust pipe within the common range of sizes.

Another object is to provide a heater of this type having a casing of uniform size adapted to surround an exhaust pipe and having means mounted on the ends thereof adapted to fit the casing upon exhaust pipes of different diameters.

Another object is to provide a sheet metal joint adapted to join the end of a tubular member with a smaller member which lies within a predetermined range of size.

Other objects and advantages will become apparent from the following description and from the drawings, in which:

Figure 1 is a side elevational view of an exhaust heater embodying the preferred form of the invention.

Fig. 2 is an enlarged elevational view of a part of the heater shown in Fig. 1.

Fig. 3 is a sectional view taken along the line 3-3 of Fig. 2.

Fig. 4 is a plan view of a sheet metal blank which has been stamped to form the part shown in Fig. 2, but before complete assembly thereof.

Fig. 5 is a side view of the sheet metal blank shown in Fig. 4.

Fig. 6 is an end view of the blank shown in Fig. 4 as viewed from below in Fig. 4.

While the invention is susceptible of vari-

ous modifications and alternative constructions, I have shown in the drawings and will herein describe in detail the preferred embodiment, but it is to be understood that I do not thereby intend to limit the invention to the specific form disclosed but intend to cover all modifications and alternative constructions falling within the spirit and scope of the invention as expressed in the appended claims.

The exemplary embodiment of the invention chosen for disclosure herein is shown as having a casing 1 mounted on an exhaust pipe 2 of a motor vehicle having a floor board 3 and comprises generally a comparatively large tubular member 4 which surrounds the exhaust pipe throughout a portion of its length and is supported thereby. The tubular member 4 and the exhaust pipe 2 are preferably arranged concentrically so as to provide an annular passage 5 through which air may be conducted to be heated by contact with the exhaust pipe. The heated air is then conducted upwardly from the casing 1 by means of a suitable conduit 6 and is discharged into the body of the vehicle through a register 7 which is preferably mounted in the floor of the vehicle.

In the embodiment herein illustrated the air for heating the car is supplied by means of a forced draft device which cooperates with the motor fan of the vehicle to force air into the forward end of the heater casing. The forced draft device illustrated comprises a funnel shaped intake member 8 adapted to be positioned in the path of the air blast created by the motor fan (not shown), and a flexible tube 9 connecting the funnel member and the forward end of the casing 1. Thus during the operation of the vehicle motor, a continuous circulation of air may be provided through the heater and into the body of the vehicle.

To provide for closing the ends of the casing 1 about any exhaust pipe which lies within the common range of sizes, I provide a sheet metal joint preferably mounted on the ends of the casing and means for attaching the joint to the exhaust pipe by the use of ordinary hand tools.

In the preferred form illustrated this joint is formed from a sheet metal blank 10 (Fig. 4) which is of substantially rectangular shape. A comparatively wide strip 11 along one edge thereof is adapted to surround the larger of the two tubular members and projects at one end beyond the main body of the blank to provide a flap 12 which in the assembled joint is arranged to overlap the end 13 of the strip as shown in Fig. 3. A plurality of apertures 14 may be provided in the flap 12 and the end 13 to permit the two to be joined as by rivets 15.

To limit the distance to which the large tubular member 4 may be inserted, an abutment 16 is provided preferably struck out from the inner of the two overlapping ends of the strip 11 and arranged to project inwardly of the joint when in assembled position to engage the end of the tube 4. In the present embodiment an aperture 17 is also provided in the strip 11 to receive a circular clamping member 18 which is adapted to connect the casing to the flexible tubing members which conduct the air to and from the heater.

To provide an inwardly converging portion extending from the end of the larger casing member 4 to meet the outer surface of the smaller exhaust pipe 2, a plurality of substantially parallel slits 19 are formed in the sheet metal blank 10 substantially at right angles to the strip 11 and extending from said strip to the opposite edge of the blank, thus forming a plurality of strips or fingers 20. It will be apparent that when the strip portion 11 is wrapped around an end of the tube 4, the free ends of the fingers may be bent inwardly toward the outer surface of the concentric pipe 2 at an acute angle thereto. When the fingers 20 are thus bent, it will be apparent that they will overlap to form a continuous inwardly converging annular wall joining the two tubular members.

In order that the fingers may overlap throughout substantially their entire length so as to produce practically an air tight joint between the tube and pipe, alternate fingers 20^a are preferably offset inwardly from the plane of the other fingers 20^b as at 21 (Figs. 4 and 5). When the alternate fingers 20^a are thus offset, the edges of adjacent fingers 20^a may converge toward each other during substantially their entire length and when the fingers 20^b are bent inwardly their inner surfaces will contact the converging edges of adjacent fingers 20^a throughout substantially their entire length, thus forming a practically air tight wall. At the ends of the fingers, portions 22 are bent into an angular position as shown in Fig. 5, so that this portion will be in substantially proper position to abut an average sized pipe and to be clamped thereto. These portions 22 are also formed with a slightly arcuate cross section (Fig. 4) so that they may be more easily clamped in position.

For the purpose of securing the end portions of the fingers in position about the smaller pipe, a ring clamp 23 is preferably employed which surrounds the end portions 22 of the fingers and is tightened thereon by a suitable screw device. In order to retain the ring clamp in operative position about the portions 22, abutments 24 are preferably formed on the fingers 20^b by bending the ends thereof outwardly as best shown in Figs. 2 and 5.

It will be apparent from the foregoing description that the invention provides an exhaust heater which may be easily and economically applied to exhaust pipes of different diameters and which is readily adapted to permit of installation by an ordinary purchaser. This adapts the heater to all makes of cars and avoids the necessity and expense of making and handling as many sizes of heater as there are different sized exhaust pipes.

It will also be apparent that a coupling member has been provided which is adapted to be economically formed from sheet metal and which will serve effectively to connect two axially aligned tubular members of different diameters with a practically air tight joint.

I claim as my invention:

1. In an exhaust heater for automotive vehicles having a casing arranged to surround a portion of an exhaust pipe of a vehicle, means of forming end closures for said casing about the exhaust pipe comprising a plurality of fingers projecting longitudinally from the ends of the casing, alternate fingers being arranged to be bent inwardly toward and at an acute angle to an exhaust pipe so as to leave angular openings between adjacent bent fingers and the other fingers bent inwardly to contact the edges of said previously bent fingers and thereby close said openings.

2. In an exhaust heater having a tubular member having inlet and outlet openings therein and surrounding an exhaust pipe to form a heating passage, means to close the ends of the passage comprising a plurality of substantially flat fingers projecting axially from the ends of said member and adapted to be bent inwardly in overlapping relation with each other and to contact said pipe at an acute angle thereto, and means for securing said fingers in contact with said pipe.

3. In an exhaust heater having a tubular member having inlet and outlet openings formed therein, said member being adapted to surround an exhaust pipe, means adapting said member for application to pipes of different diameters, said means comprising sheet metal members attached to the ends of said tubular member and having a plurality of integrally formed fingers adapted to be bent inwardly into contact with and at an acute angle to the outer surface of the exhaust pipe, a ring clamp for securing the ends of

said fingers in such contact, and means on said fingers to retain said ring clamp in position thereon.

4. A connecting device for joining two tubular members of different diameters which are substantially in axial alinement, said device comprising a band adapted to surround the end of the larger member, a plurality of fingers formed integrally with said band and extending longitudinally from the end of said tubular member, said fingers being adapted to be bent inwardly into converging and overlapping relation so that the ends thereof contact and surround the smaller tubular member at an acute angle thereto, and means for securing the ends of said fingers in said position.

In testimony whereof, I have hereunto affixed my signature.

20 HERBERT P. RENWICK.
